UNITED STATES PATENT OFFICE

132,520

DESIGN FOR A CYCLOPLANE

Peter Tom Tomasini, Sunnyside, N. Y.

Application January 10, 1942, Serial No. 105,100

Term of patent 7 years

To all whom it may concern:

Be it known that I, Peter Tom Tomasini, residing at Sunnyside, in the county of Queens and State of New York, have invented a new, original, and ornamental Design for a Cycloplane, of which the following is a specification, reference being had to the accompanying drawings, forming part thereof.

Figure 1 is a side elevational view of a cycloplane, showing the new design, a portion of the

propeller being broken away for convenience in illustration.

Figure 2 is a front view of the cycloplane.

Figure 3 is a perspective view; and

Figure 4 is a top plan view thereof, with the wings in folded position.

I claim:

The ornamental design for a cycloplane, as shown and described.

PETER TOM TOMASINI.

CERTIFICATE OF CORRECTION.

Design No. 132,520.

May 26, 1942.

PETER TOM TOMASINI.

It is hereby certified that error appears in the above numbered patent requiring correction as follows: In the drawing, Sheet 2, Figure 4 should appear as shown below instead of as shown in the patent -

Fig. 4

and that the said Letters Patent should be read with this correction therein that the same may conform to the record of the case in the Patent Office.

Signed and sealed this 28th day of July, A. D. 1942.

(Seal)

Henry Van Arsdale,
Acting Commissioner of Patents.
